(57) **CLAIM**

The ornamental design for a dental hand instrument with opposing smooth wavy handgrip portions, as shown and described.

DESCRIPTION

FIG. 1 is a perspective view of a dental hand instrument with

opposing smooth wavy handgrip portions. Hatchet tips are shown attached at opposing ends of the dental hand instrument with opposing smooth wavy handgrip portions in broken lines for illustrative purposes only and form no part of the claimed design.

FIG. 2 is a side view of the dental hand instrument with opposing smooth wavy handgrip portions. Hatchet tips are shown in broken lines for illustrative purposes only and form no part of the claimed design.

FIG. 3 is a top plan view of the dental hand instrument with opposing smooth wavy handgrip portions without a tip.

FIG. 4 is a side view of the dental hand instrument with opposing smooth wavy handgrip portions. A composite packer tip is shown attached at each end of the dental hand instrument with opposing smooth wavy handgrip portions in broken lines for illustrative purposes only. The tips form no part of the claimed design.

FIG. 5 is a side view of the dental hand instrument with opposing smooth wavy handgrip portions. An explorer tip is shown attached at each end of the dental hand instrument with opposing smooth wavy handgrip portions in broken lines for illustrative purposes only. The tips form no part of the claimed design.

FIG. 6 a side view of the dental hand instrument with opposing smooth wavy handgrip portions. The dental hand instrument with opposing smooth wavy handgrip portions is shown with a mirror tip at one end and a composite packer tip at the opposite end in broken lines for illustrative purposes only. The tips form no part of the claimed design; and,

FIG. 7 a side view of the dental hand instrument with opposing smooth wavy handgrip portions. The dental hand instrument with opposing smooth wavy handgrip portions is shown with a hatchet tip at one end and an explorer tip at the opposite end in broken lines for illustrative purposes only. The tips form no part of the claimed design.
